UNITED STATES PATENT OFFICE.

FRANK E. LUMLEY, OF CHICAGO, ILLINOIS.

VENTILATING DEVICE FOR TOILETS.

Application filed October 18, 1926. Serial No. 141,298.

The object of the present invention is to provide ventilating means for toilets.

Another object of the invention is the provision of a device in combination with a suction machine whereby the foul air is drawn 5 from the toilet bowl.

A still further object of the invention is the provision of a ventilating device in association with the toilet bowl which may be 10 automatically set in operation when the seat is occupied and in which the operation is instantly prevented on leaving the seat unoccupied.

In modern hotels and office buildings a 15 suction machine is used, usually located in the basement to which pipes lead from each floor of the building, for sweeping and other purposes, and therefore the object of the present invention is the provision of a ventilating device of the character above stated 20 which may be used in connection with such suction machine.

With the above general objects in view and others that will appear as the nature of 25 the invention is better understood, the same consists in the novel construction, combination and arrangement of parts hereinafter more fully described, illustrated in the accompanying drawings and pointed out in the 30 appended claims.

In the drawings forming a part of this application, and in which like designating characters refer to corresponding parts throughout the several views,

35 Fig. 1 is a side elevational view of the toilet bowl with the cooperating parts of the ventilating device in their inoperative condition;

Fig. 2 is a side view partly in section and, 40 partly in elevation, of the bowl and the ventilating device while the latter is in operative position;

Fig. 3 is the top view, partly in elevation and partly in section of the valve mechanism 45 forming part of the ventilating device; and

Fig. 4 is a side view, partly in elevation and partly in section of the valve mechanism constituting a part of the ventilating device.

50 The ventilating device cooperating with the toilet bowl 10 embodies a cup-shaped casing 11 having an integrally formed pipe 12. By means of flange 13 and screws 14 said casing is attached to the wall 15. Pipe 16 55 leads to the suction machine which is not

shown in the drawings, is receivable through wall 15 within cup-shaped casing 11 and pipe 12. Section of pipe 16 closely fits within said pipe 12 so as to provide air-tight connection between the two pipes. Section of pipe 16 which remains within cup-shaped casing 11 is provided with a valve casing 17 and valve stem 18. On line with said valve stem 18 opening 19 is provided in the cup-shaped casing 11. Cover 20 normally maintains said opening closed. Said opening provides access to valve stem 18 for the purpose of opening or shutting off the valve in pipe 16 for either permitting or shutting off the action of the suction machine upon the ventilating device. Pipe 12 on the lower portion of its periphery is provided with a threaded opening 21 for receiving the end of pipe 22 which leads to the toilet bowl 10. The other end of said pipe 22 remains within bowl 10 and is covered with a mesh 23 for preventing splashes of water to enter said pipe.

70 The invention further embodies a substantially cubic block 24 which is positioned on line with pipe 12. Two parallel side plates 25 and 26 mounted at the end of pipe 12 by screws 27 and 28, respectively, maintain said block 24 in operative position in respect of pipe 12, said plates 25 and 26 being secured to said block 24 by means of screws 29 and 30, respectively.

80 Valve rod 31 is receivable by one of its ends within the enlarged mouth of pipe 12, the movement of said valve rod 31 within said pipe 12 being limited by shoulder 32 formed within said pipe 12, while the other outer end of valve rod 31 is receivable within bore 33 made in the cubic block 24. Substantially at the central portion of said valve rod 31 and at two diametrically opposite 85 points on its periphery on horizontal line, said valve rod 31 is provided with two pins 34 and 35 providing bearings for washers 36 and 37. Positioned upon said valve rod 31 at the point adjacent the end of pipe 12 is collar 38, which at its outer end is provided with an outwardly projecting flange 39. Interposed between the inner end of block 24 and washer 37 is a coil spring 40 encompassing the valve rod 31. Coil spring 41, which, 90 however, is heavier than spring 40 is positioned upon valve rod 31 and remains interposed between washer 36 and flange 39 upon collar 38.

100 The outer ends of plates 25 and 26 carry 105

110

a U-shaped locking plate 42, which at its two ends is pivoted upon said plates and the inner end of block 24 by means of screws 43 and 44 and spacers 45 and 46. Said U-shaped plate 42 at one of its ends has an upwardly projecting extension 47 which at its upward termination has a collar 48 pivoted on the pivot point 49, all for the purposes hereinafter stated.

10 Collar 38 has two outwardly projecting pins 50 and 51 for pivoting thereupon the upper ends of L-shaped plates 52 and 53, respectively. The lower horizontal portions of said plates 51 and 52 converge toward each other and receive therebetween arm 54 wherein it is held in rigid condition by means of bolts and nuts 55. The outer end of said arm 54 has a U-shaped plate 56 pivoted thereto by its ends upon pin 57. The bent portion of the U-shaped plate 56 receives the end of rod 58. The adjacent end of said rod 58 is threaded for receiving thereupon nut 59 which remains within said U-shaped plate 56. By means of said nut 59 the length of rod 58 may be regulated as is required for the operativeness of the device. The outer end of rod 58 has chain 60 attached thereto, while the other end of said chain 60 is attached to the upper end of a substantially L-shaped bar 61. The foot portion of said L-shaped bar 61 is fastened to the lower face of seat 62 near the point at which said seat is hinged to the bowl 10.

35 The operation of said U-shaped locking plate 42 is had through the medium of rod 63 which is receivable within collar 48 wherein it is adapted for longitudinal sliding movement. The end of said rod 63 is threaded for receiving thereupon nut 64 by means of which locking plate 42 may be raised as will be hereinafter described. The outer end of said rod 63 is provided with nut 65, and interposed between said nut 65 and collar 48 is a coil spring 66 for the purposes hereinafter stated. The other end of said rod 63 is pivoted to L-shaped bar 67 on pin 68. The foot portion of said L-shaped bar 67 is attached to the lower face of the cover 69 near to the point where said cover 69 is hingedly connected to seat 62.

55 The suction machine hereinabove mentioned at all times maintains a vacuum in pipe 12 when valve 18 remains open. The action of said suction machine is communicated to bowl 10 by means of pipe 22 through which foul air from bowl 10 is passed to suction machine. Rod 31 acts as a valve for either opening or closing the communication 21 with pipe 12. When seat 62 remains in an unoccupied position illustrated by dotted lines on Fig. 2 spring 40 remains expanded pressing valve rod 31 toward shoulder 32, thus keeping the inlet 60 21 of pipe 22 closed and out of communica-

tion with pipe 16 of the above mentioned suction machine. As soon as the seat by virtue of its occupancy is pressed downwardly toward the upper edge of bowl 10, the position illustrated by full lines on Fig. 2, plates 52 and 53 are caused to exert compression of spring 40, causing its contraction, it being observed that spring 41 by virtue of its being heavier than spring 40 remains unaffected by the action of said plates 52 and 53 and the compression of spring 40. Thus, due to the shifting action and pressure of said plates 52 and 53 upon flange 39, spring 41, washer 36 and pins 34 and 35, valve rod 31 is caused to slide in the reverse direction for opening vent 21 of pipe 22. When said seat 62 remains in contact with the bowl 10 and is occupied cover 69 is of course open, the position illustrated on Fig. 2, and by means of L-shaped bar 67, rod 63 and nut 64 causes upward tilting movement of U-shaped locking plate 42 permitting the sliding movement of valve rod 31 within block 24 by virtue of the action of plates 52 and 53 hereinabove described. It will therefore be seen that when cover 69 is opened and seat 62 is occupied, position illustrated in full lines on Fig. 2, locking plate 42 will remain tilted permitting sliding movement of valve rod 31 for opening vent 21 of pipe 22. On releasing seat 62 from contact with the edge of bowl 10 spring 40 is sufficiently strong due to its expanding action and consequent pressure upon pins 34 and 35 not only to force the inner end of valve rod 31 toward shoulder 32 for closing vent 21 of pipe 22 but also to maintain said seat 62 in tilted position illustrated by dotted lines on Fig. 2.

40 As hereinabove stated cover 69 through L-shaped bar 67, rod 63, nut 64 and spring 66 is adapted for operating U-shaped locking plate 42. When said cover 69 remains open bar 67 exerts a backward pressure upon rod 63 which in turn through nut 64 exerts rearward pressure upon collar 48 causing rearward tilting of extension 47 and consequent upper shifting movement of the central portion of plate 42 bringing the same out of contact with the outer end of block 24, thus permitting the unobstructing sliding movement of valve rod 31 within said block. When said cover 69 remains in open position illustrated on Fig. 2, and plate 42 remains in consequence in upper tilted position, spring 66 is expanded. When said cover 69 shall be brought downwardly to tilted position to correspond with the position of seat 62, the position illustrated by dotted lines on Fig. 2, L-shaped bar 67 will be shifted upwardly to the position substantially corresponding with the position of bar 61, rod 63 will be retracted together with nut 64 from collar 48, and spring 66 will then be caused to contract and exert 45 50 55 60 65 70 75 80 85 90 95 100 105 110 115 120 125 130

pressure upon the adjacent end of said collar 48 causing plate 42 to drop down and lock the outer end of block 24.

From the hereinabove made description it will be apparent that when said seat 62 and cover 69 remain in tilted position locking plate 42 will cooperate with the outer end of block 24 for preventing the outward shifting movement of valve rod 31. In that latter position of seat 62 and cover 69 plates 52 and 53 will remain in the position illustrated by dotted lines on Fig. 2, that is in abutment with the outer end of pipe 12, by virtue of the expanding action of springs 40 and 41.

When seat 62 and cover 69 are pressed downwardly upon the bowl 10, position illustrated on Fig. 1, the position of locking plate 42 will remain unaltered from the position described in the last preceding paragraph. By bringing said cover 69 to the position shown on Fig. 1 rod 63 will become further retracted bringing nut 64 farther away from collar 48, and consequently spring 66 will become more contracted. When said seat 62 remains in closed position illustrated on Fig. 1 the action of plates 52 and 53 upon rod 31 through springs 40 and 41 will not affect rod 31, owing to the fact that locking plate 42 prevents the shifting of said rod. From the drawings and herein made description it will be apparent that when seat 62 and cover 69 remain in closed position illustrated on Fig. 1 the consequent pulling action of plates 52 and 53 will merely compress spring 41 without affecting the position of valve rod 31 illustrated on Fig. 3.

From the various cooperating positions of seat 62 and cover 69 hereinabove described it may be briefly stated that when said seat remains in occupied position illustrated on Fig. 2 and cover 69 remains in open position, the valve rod 31 will become retracted from within pipe 12 so as to open vent 21 and provide the communication thereof with pipes 12 and 16, thus to cause the operation of suction to exert its influence upon bowl 10 through pipe 22. When seat 62 and cover 69 remain in tilted position illustrated by dotted lines on Fig. 2, valve rod 31 will remain within pipe 12 by virtue of expanding action of spring 40. When in that latter position of seat 62 springs 40 and 41 are sufficiently strong to hold plates 52 and 53 in retracted position, position shown by dotted lines on Fig. 2, and maintain said seat 62 and cover 69 in tilted position. It is therefore apparent that when said seat 62 and cover 69 remain in said last mentioned tilted position communication of pipe 22 with pipes 12 and 16 is closed by virtue of the fact that valve rod 31 locks vent 21.

When said seat 62 and cover 69 are both pressed toward bowl 10, the common posi-

tion of said cover when the occupant uses the bowl for dressing purposes, the valve rod 31 will remain in abutment with shoulder 32 for closing vent 21. In that latter position of said seat 62 and cover 69 locking plate 42 will remain in abutment with the outer end of block 24 preventing the outward shifting of valve rod 31 from pipe 12, while plates 52 and 53 will remain retracted causing the compression of spring 40 without affecting in any manner the valve rod 31.

From the hereinabove made description it will be apparent that when said seat 62 and cover 69 are both either raised or tilted or pressed toward bowl 10 the ventilating device will remain inoperative. The operation of the ventilating device will be had only when seat 62 is occupied and cover 69 is raised.

While there is described herein a preferred embodiment of the present invention, it is nevertheless to be understood that minor changes may be made therein without departing from the spirit and scope of the invention as claimed.

What I claim as new is:

1. In a ventilating device for toilets, the combination with a bowl, a seat therefor normally slightly spaced from the bowl, a cover for the seat, and a suction system communicating with the bowl; of means interposed in the system and connected with the seat for opening communication between the system and the bowl when the seat is moved to rest upon the bowl, and to close communication when the seat is in its normal spaced position, and other means connected with the cover for the seat and cooperative with said first named means for locking the said first named means in closing position with respect to communication between the bowl and system when the cover is upon the seat.

2. In a ventilating device for toilets, the combination with a bowl, a seat therefor, a cover for the seat, and a suction system communicating with the bowl; of means interposed in the system and connected with the seat for opening communication between the system and the bowl when the seat is occupied, and means connected with the cover for the seat and cooperative with said first named means for locking said first named means in closing position with respect to communication between the bowl and suction system when the cover is in closed position.

3. In a ventilating device for toilets, the combination with a bowl, a seat therefor, a cover for the seat, and a suction system communicating with the bowl; of means for maintaining the seat slightly raised from the edge of the bowl, means interposed in the system and connected with the seat for opening and closing communication between

the system and bowl respectively when the seat is lowered, or raised, means connected with the cover and cooperating with the first named means for locking said means in 5 a closing position with respect to communication between the system and bowl when the cover is upon the seat and opening communication when the cover is off the seat or in raised position, and means for maintaining communication between the system and bowl closed when the seat is engaged with the bowl and the cover in its normal closing position.

4. In a ventilating device for toilets, the 15 combination with a bowl, a seat therefor, a cover for the seat, and a suction system communicating with the bowl, of automatic means for permitting communication of the suction system with the bowl when the seat 20 is occupied, and automatic means for locking the first named means in closing position when the cover is upon the seat.

5. In a ventilating device for toilets, the combination with a bowl, a seat, a cover, and 25 a suction system; a valve in the suction sys-

tem, means connected with the seat for operating the valve, a locking element associated with the valve, and means associated with the cover for opening or closing the locking element, said last named means being adapted to open the locking element when the cover remains open for permitting opening of said valve by said first named means when said seat is occupied. 30

6. In combination with a toilet having a bowl, a seat and a cover; a suction machine; a pipe connecting said bowl with said suction machine; a valve in said suction machine; means upon said seat for operating said valve; a locking plate associated with said valve; and means associated with said cover for opening or closing said locking plate; said last named means being adapted to open said locking plate when the cover remains open for permitting the retraction of said valve from said pipe by said first named means when said seat remains occupied. 35

40 In testimony whereof I affix my signature.
FRANK E. LUMLEY. 45
